OSCAR KLEINSCHMIT, OF LEIPZIG-PLAGWITZ, GERMANY, ASSIGNOR TO GEBRUDER BREHMER, MASCHINEN-FABRIK, OF LEIPZIG-PLAGWITZ, GERMANY

PAPER FOLDING MACHINE

Application filed March 6, 1930, Serial No. 433,684, and in Germany November 2, 1929.

In paper folding machines in which the sheets are fed between feed rollers into guides or pockets for forming folds with associated folding rollers by the well known buckling process the outer ends of the upper and lower bars that constitute in the form of a grid, the aforesaid pockets are usually brought as close as possible to the feed rollers, but a small clearance space must be left 10 to allow for the slight movement apart of the rollers when the sheet is passed between them. This space is quite sufficient to permit of the passage of a paper sheet so that it sometimes happens that in the event of the 15 front edge of a sheet turning up or down when it leaves the rollers the sheet is liable to pass under or over the pocket through the clearance space aforesaid with the result that the rollers are clogged and the smooth working 20 of the machine is hindered.

This disadvantage is overcome according to the present invention and the sheets are guided with certainty into the pocket by extending the bars of the pocket frame to pass 25 between the adjacent operative rollers so that in themselves they form guides for the sheet, the ends of the extended bars being preferably curved so that in the case of the upper bars they present with the surface of the 30 feed table a funnel-shaped guide for the sheet to the feed rollers and in the case of the lower bars they ensure the passage of the sheet from the feed rollers into the pocket obviating its passage between the ends of 35 the lower bars and the periphery of the folding roller associated with the lower feed roller and preventing it from fouling the lower bars which sometimes happens with the present construction of pocket.

40 This extension of the lower bars is, however, not essential as the object aimed at can be equally well attained by lowering the folding roller so that the sheet will pass into the pocket even if its edge be turned down 45 when it leaves the feed rollers.

The nature of the invention will be more clearly understood by reference to the accompanying somewhat diagrammatic drawings in which similar reference characters relate to like parts in both figures.

50

Figure 1 shows the feed rollers and associated folding roller and the entrance to the pocket.

Figure 2 is a plan view of the same parts.

In the said drawings the reference letter *a* 55 represents the feed table, *b* the upper feed roller, *c* the lower feed roller, *d* the upper bars of the pocket frame, *e* the lower bars, *f* the pocket and *g* the folding or buckle roller that is associated with the lower feed roller *c* 60 to form the first fold in the well known manner.

As previously indicated and as will be clear from the drawings according to the present improvements the upper bars *d* are 65 extended to pass between the feed rollers *b* and *c* the roller *b* being grooved or reduced in diameter as shown at *h* to allow for the passage of the bars *d* without interference to the feed of the sheet between the rollers *b* 70 and *c*. The ends of the bars *d* are preferably curved or bent upwardly as shown at *k* so that they form with the flat surface of the feed table *a* a funnel shaped guide or series 75 of guides to the sheet passing to the feed rollers *b* and *c* and ensure its passage into the pocket *f*.

The lower bars *e* may also be extended to pass between the rollers *c* and *g* as shown in dotted lines in Figure 1, the roller *g* being 80 grooved or reduced in diameter for this purpose.

What I claim is:—

1. In a folding machine, having feeding rollers and a folding roller, upper and lower 85 pocket frame bars having extensions passing between the adjacent operative feeding and folding rollers.

2. In a folding machine, having feeding rollers, upper pocket frame bars having ex- 90

tensions passing between the feed rollers, one of said rollers being grooved to allow of the passage of said bars and the outer ends of said bars being curved to present funnel shaped guides for the paper sheet.

3. In a folding machine, having folding rollers, lower pocket frame bars having extensions passing between the folding rollers, one of said rollers being grooved to allow 10 of the passage of said bars, and the outer ends of said bars being curved to conform to the periphery of said grooved roller.

In testimony whereof I affix my signature.
OSCAR KLEINSCHMIT.
